UNITED STATES PATENT OFFICE.

SAREPTA R. MOORE, OF DETROIT, MICHIGAN.

FOLDING BED.

No. 824,734.

Specification of Letters Patent.

Patented July 3, 1906.

Application filed June 12, 1905. Serial No. 264,939.

To all whom it may concern:

Be it known that I, SAREPTA R. MOORE, a citizen of the United States, residing at Detroit, in the county of Wayne and State of Michigan, have invented new and useful Improvements in Folding Beds, of which the following is a specification.

This invention relates to folding beds, and the object thereof is to provide a bed of such class which shall be simple in its construction, strong, durable, light in weight, compact when folded, so as to require but little space, having the top of the bed-bottom-inclosing case acting as a mantel or shelf, easily taken apart, so the same can be conveniently shipped or transported, and comparatively inexpensive to manufacture.

With the foregoing and other objects in view the invention consists of the novel construction, combination, and arrangement of parts hereinafter more specifically described, illustrated in the accompanying drawings, which form a part of this specification, and particularly pointed out in the claims hereunto appended.

In describing the invention in detail reference is had to the accompanying drawings, wherein like reference characters denote corresponding parts throughout the several views, and in which—

Figure 1 is a side elevation of a folding bed constructed in accordance with this invention with the bed in its lowered position and ready for use. Fig. 2 is a like view with the bed folded. Fig. 3 is a front view when folded. Fig. 4 is a front elevation of the bed-inclosing case with the bed-bottom and bedding removed, and Fig. 5 is a detail of one of the front supporting-legs for the bed.

Referring to the drawings, the inclosing case for the bed-bottom and bedding comprises a forwardly-projecting flat top and bottom member, (indicated by the reference characters 1 and 2, respectively,) the top member 1 acting as a mantel, shelf, or support and the bottom member 2 acting as a base for the casing. The inclosing case further comprises a pair of back members 3 4, which are connected in a manner as hereinafter set forth to the members 1 2 and are spaced a suitable distance apart—that is to say, near the ends of the said members 1 2. The top member 1 is connected to the back members 3 4 through the medium of two pairs of

brackets 5 6, respectively. The brackets 5 55 are secured to the inner edge of the members 3 4 at the top thereof and are also secured to the lower face of the member 1 at the rear thereof. The brackets 6 are secured to the front of the members 3 4 near the top thereof and also to the underneath face of the member 1 near the sides thereof. The bottom member 2 is secured to the members 3 4 through the medium of two pairs of brackets 7 8, respectively. The brackets 7 are secured against the inner edge of the members 3 4 near the bottom thereof and to the upper face of the member 2. The brackets 8 are secured to the front of the members 3 4 near the bottom thereof and to the upper face 70 of the member 2. Preferably the holdfast means for all the brackets are screws.

The reference character 9 denotes the bed-bottom, and 10 the bedding. The bed-bottom may be of any suitable construction and 75 is preferably so positioned with respect to the inclosing case that the ends of said bed-bottom will be arranged at the sides of the case, although the bed-bottom can be positioned so that the sides thereof will be at the sides of 80 the case; but the manner of positioning the bed-bottom as shown enables the employment of a case of much less height than if the sides of the bed-bottom were arranged substantially parallel with the sides of the case 85 when the bed is folded. Secured to the ends of the bed-bottom 9 and extending longitudinally of the bottom, at the front and rear thereof, are the tubular rods 11 12, the former being arranged at the front of the 90 bed-bottom and the latter at the rear of the bed-bottom. The rod 11 acts as an intermediate support for the bed-bottom when the same is in its lowered position, the primary support being a pair of legs 13. The rod 11 95 when the bed is folded acts as a suspension means for the legs 13. Each of the legs 13 is loosely mounted upon the rod 11, so that said legs will swing thereon, and each of said legs consists of two sections 14 and 15, Fig. 5, 100 which are secured together through the medium of the holdfast devices 16. The section 14 of each of the sections of each pair of sections which form the supporting-legs 13 is constructed at its upper end with a semicylindrical portion 17 and at its lower end with an angularly-extending portion 18. The section 15 is of like construction, with this

exception, that the angularly-projecting portion 19 extends in an opposite direction with respect to the angularly-projecting portion 18 of the section 14, and the semicylindrical portion 20 of the section 15 is arranged in a reverse manner with respect to the semicylindrical portion 17 of the section 14. When the sections 14 15 of each supporting-leg are secured together, a cylindrical portion is formed at the upper end thereof and which embraces the rod 11, the diameter of said cylindrical portion being such that the leg can swing upon the rod 11, and when the said sections 14 and 15 are secured together to form a leg the angularly-projecting portions 18 and 19 provide the leg with a foot which is adapted to rest upon the floor when the bed is in its lowered position. By such a construction if either one of the legs 13 should become broken the same can be removed and a new one readily substituted. The rod 12 acts as an intermediate support for the bed when in its lowered position and also when the bed is folded. Furthermore, said rod 12 acts as a pivot when moving the bed from an upright to a lowered position or from a lowered to an upright position. The primary support which associates with the rod 12 consists of a pair of stationary inverted-V-shaped brackets 21, having their tops formed in a semi-oval or semicylindrical manner, as at 22, said semi-oval or semicylindrical portion 22 forming a pivot-seat for the rod 12. The inverted-V-shaped supporting brackets 22 are secured, as at 23, to the upper face of the bottom member 2 of the frame near each end thereof. By such a construction the bed-bottom 9 can be readily lifted off the brackets 21.

When the bed is folded, it is adapted to be hidden from view through the medium of a drapery which is attached to the sides as well as the front edges of the top member 1 of the inclosing case. Any suitable form of drapery can be employed, and it is thought unnecessary to show it. The brackets 21 are secured near the front edge of the member 2, so that when the bed-bottom and bedding are elevated to within the inclosing case the latter will have a tendency to lean toward the rear of said case, thereby preventing the accidental lowering of the bed-bottom and bedding if holdfast devices are not employed to retain the bed-bottom and bedding in an upright position within the inclosing case. Suitable stops are provided upon the rods 11, as at 24, to prevent the longitudinal movement of the legs 13, and stops 25 are provided upon the rod 12, so that the same can be properly positioned upon the brackets 21.

From the foregoing description, taken in connection with the accompanying drawings, it will be evident that a folding bed is set up

which is simple in its construction and very compact in form, as well as one that can be readily taken apart, so that it can be conveniently shipped or transported. Furthermore, as described, it is entirely unnecessary to use nails in the structure. Then, again, if the supporting-legs 13 become broken they can be readily replaced, owing to the manner in which said legs are set up, and it is thought the many advantages of such a construction of folding bed can be readily understood from the foregoing description, taken in connection with the accompanying drawings.

If desired, the supporting-brackets can be fixed to the floor, and the top member of the casing can be an ordinary shelf, which is secured to the wall and the drapery connected to said shelf, so that the bed proper can be folded to a position below the shelf and inclosed in the drapery. By such an arrangement the casing can be dispensed with.

Having thus fully described my invention, what I claim as new, and desire to secure by Letters Patent, is—

1. A folding bed having legs for supporting the bed in its lowered position, each of said legs consisting of two sections, each formed with a semicylindrical portion and an angularly-extending portion, and means for securing the said sections together, thereby forming a leg having at its top a cylindrical portion and at its bottom a foot.

2. A folding bed comprising the combination with the bed proper, of a pair of tubular rods suitably connected with the bed, a pair of supporting-legs each formed of two sections suitably connected together and each of said legs encircling at their upper ends one of said rods, the sections of each leg bent at their bottoms to form a foot extending laterally on both sides of the lower end of the leg, and a pair of inverted-V-shaped supporting brackets having their upper ends formed in a curvilinear manner to constitute seats to receive the other of said rods.

3. A folding bed having legs for supporting the bed in its lowered position, each of said legs consisting of two sections, each formed with a semicylindrical portion and an angularly-extending portion, and means for securing the sections together, thereby forming a leg having at its top a cylindrical portion and at its bottom a foot, combined with a rod extending through the cylindrical portion of each of the legs for connecting the legs to the bed.

4. A folding bed comprising the combination with the bed proper, of a tubular rod connected to bed at the head thereof, a tubular rod connected to the bed at the foot thereof, a pair of inverted-V-shaped supporting brackets having their upper ends formed in a curvilinear manner to constitute seats to re-

ceive the rod at the head of the bed, and a pair of swinging legs having their tops provided with a hollow cylindrical portion to receive the rod at the foot of the bed, said legs having the lower end thereof bent to form a foot extending laterally on both sides of the lower end of the leg.

In testimony whereof I have hereunto set my hand in presence of two subscribing witnesses.
